WILLIAM THOMPSON AND J. E. HALL, OF CLEVELAND, OHIO.

Letters Patent No. 71,665, dated December 3, 1867.

IMPROVED CARBURETTING-APPARATUS.

The Schedule referred to in these Letters Patent and making part of the same.

TO ALL WHOM IT MAY CONCERN:

Be it known that we, WILLIAM THOMPSON and J. E. HALL, of Cleveland, in the county of Cuyahoga, and State of Ohio, have invented certain new and useful Improvements in a Carburettng-Apparatus; and we do hereby declare that the following is a full and complete description of the same, reference being had to the accompanying drawings, making a part of this specification, in which—

Figure 1 is a side view of the apparatus.

Figure 2 is a view of the inside.

Figure 3 is a vertical transverse section.

The other figures are detached sections, to which reference will be made.

Like letters of reference refer to like parts in the several views.

A, fig. 1, is the shell or case of the apparatus, which may be constructed of tin or galvanized sheet iron, and of any required capacity. Within this shell is a lining of perforated tin, B, fig. 3, the diameter of which is considerably less than the case, thus leaving a space all around between the tin, and which space is partitioned off into sections corresponding in number to the number of dependent spouts or sleeves C, each sleeve having its separate section. These several spouts and sections are filled with cotton, D, or any other suitable flocculent material, the purpose of which will be hereafter shown. E, Figure 7, is a circular float, the radial arms F, figs. 2 and 3, of which reach out towards the centre of the case, which are then turned upward and united at the top, and connected to a wooden standard or guide, G, enclosed within the induction-pipe H, and in which it rises upward and downward as the float may affect it, as will hereafter be described. From the end of this standard or guide projects a point, I, on which is the agitator J, Figure 5, which consists of an outer shell or case, K, fig. 3. Within this shell is an annular chamber, L, in the upper end of which are arranged the fan-like wings M, Figure 6, and between the walls of the chamber and case are projected the spiral wings N, also indicated by dotted lines in fig. 5, the purpose of which will hereafter be shown. Projecting from the sides of the shell, and communicating with the space between the walls of the shell and chamber, are tubular arms O, provided with dependent ears P. This agitator, when suspended upon the float, as shown in fig. 3, is then covered with a double top of perforated tin, Q, fig. 4, the space between which is filled with cotton-wicking or other like material, as is the space between the case and perforated lining B, thus surrounding the agitator with a perforated top and lining, also with a material of a fibrous texture. Projecting from the top of the agitator, and penetrating through the cover Q into the cone R, is a standard, S, the purpose of which will presently be shown.

Having thus indicated the construction and arrangement of the several parts of the apparatus, the practical application and operation of the same are as follows: The carburettor is placed in any convenient out-of-the-way place, between the gas-meter and burners, and which is connected to the meter by the pipe H, through which the gas is inducted into the apparatus. A certain quantity of gasoline, or any fluid highly charged with carbon, is poured into the apparatus through the supply-pipe T, fig. 1, until the float rises up to about the height of the dotted line a, fig. 3, which will be ascertained by the point of the standard S, as seen through the eye-glass U, fig. 1, an index being arranged to indicate the quantity in the machine. As above observed, the gas is inducted into the machine through the pipe H, to the top of the chamber L, through which it passes, thence down between the walls of the chamber and shell, and out at the bottom through the tubular arms O; thence out of the sides of which, through the ports b, into the fluid, and from which it escapes to the outside of the agitator into the space surrounding it above the fluid. From this space the gas escapes to the top of the apparatus, by being compelled first to pass through the perforated lining and top, as well as through the filling between them, and from which it passes through the eduction-pipe to the burners. By this course it will be evident that the gas, as it leaves the apparatus, must be highly charged with carbon, first by passing through the fluid, and secondly by passing through the lining and cotton, which latter, by the action of capillary attraction, has become fully saturated with the fluid, and thus giving to the fluid a very large evaporating-surface, whereby it is brought more immediately and largely in combination with the gas, and thus carburettng the same in the most complete manner. In order to facilitate the evaporation of the fluid, and thereby produce a more immediate and intimate mingling of the gas and fluid, or the vapors of the fluid, the float above referred to, as it is brought up, is made to rotate by the pressure exerted upon the fan-like wings M and the spiral wings

N as the gas is passing through and over them; so also, as the gas escapes from the tubular arms O through the ports b, the reaction of the flowing gas contributes to the rotating of the agitator, and thus, by the direct and reactive energy of the gas, the agitator is kept revolving and agitating the fluid by means of the dependent ears P, and the evaporation therefore largely increased, and the purpose of carburetting the gas more fully and speedily effected.

What we claim as our improvement, and desire to secure by Letters Patent, is—

1. The agitator J, constructed with an annular chamber, L, wings M and N, and tubular arms O, in the manner and for the purpose substantially as set forth.
2. Perforated lining B, top Q, spouts or sleeves C, and cotton, D, or its equivalent, as arranged, in combination with the float E and agitator J, in the manner and for the purpose substantially as described.
3. The float E, agitator J, constructed as described, in combination with a carburetter, in the manner and for the purpose substantially as described.
4. The herein-described apparatus, provided with a float and a revolving agitator, constructed as described, whereby the carburetting-fluid is agitated for the purpose of largely increasing its evaporation or elimination, substantially as and for the purpose set forth.

WILLIAM THOMPSON,
J. E. HALL.
